CLAIM

The ornamental design for a trac-beam cover, as shown and described.

DESCRIPTION

FIG. 1 is a perspective view of the trac-beam cover showing my new design;

FIG. 2 is a front view of the design of FIG. 1;

FIG. 3 is a side view of the design of FIG. 1;

FIG. 4 is another side view of the design of FIG. 1;

FIG. 5 is a back view of the design of FIG. 1;

FIG. 6 is an end view of the design of FIG. 1; and,

FIG. 7 is another end view of the design of FIG. 1.

The portion of the figures shown in phantom lines is for illustrative purposes only and forms no part of the claimed invention.
